Inventor:

Henry Edward Randall

UNITED STATES PATENT OFFICE.

HENRY EDWARD RANDALL, OF NORTHAMPTON, COUNTY OF NORTHAMPTON, ENGLAND.

BOOT OR SHOE.

SPECIFICATION forming part of Letters Patent No. 293,354, dated February 12, 1884.

Application filed April 28, 1883. (No model.) Patented in England December 1, 1882, No. 5,739; in France April 18, 1883, No. 154,938; in Belgium April 27, 1883, No. 61,240; in Canada August 10, 1883, No. 17,439, and in Italy September 30, 1883, XVII, 15,732, and XXXI, 345.

To all whom it may concern:

Be it known that I, HENRY EDWARD RANDALL, a subject of the Queen of Great Britain, residing at Northampton, in the county of Northampton, England, have invented new and useful Improvements in the Manufacture of Boots and Shoes, of which the following is a specification.

This invention relates more particularly to improvements in the manufacture of lawn-tennis, boating, or cricketing shoes, the object of the improvements being to improve their appearance, lessen the cost of their manufacture, and to increase their durability.

Hitherto it has been the practice to fix the india-rubber soles of lawn-tennis and similar shoes onto the leather sole my means of solution, and this mode of fixing possesses disadvantages. Among others, the solution becomes soft under the effect of heat, and the india-rubber sole in consequence frequently comes away from the leather sole. A rubber sole has also been split at its edge, a portion of such split part being stitched to the shoe, and the other portion turned down and cemented over these stitches. Rubber soles have also been made with beveled edges and bordered with a leather strip of the same thickness, and having a beveled inner edge, such leather border being secured to the boot or shoe by cementing, pegging, or sewing. These methods are expensive and not sufficiently durable and satisfactory. Now, by my invention these defects are remedied and india-rubber soles connected to the leather soles according to my improvements are not liable to leave the leather sole from the effects of heat or other cause, nor can any portions of the rubber outermost sole become separated from each other; and my invention consists in constructing the boot or shoe with a flanged rubber outer sole stitched through such flange to the leather sole of the shoe, all as clearly hereinafter described.

In order to enable my improvements to be fully understood, I will proceed to describe the same by reference to the accompanying drawings, in which—

Figure 1 is a side elevation of a lawn-tennis shoe manufactured according to my invention.

Fig. 2 is a plan of the sole of the same. Fig. 3 is a plan showing the india-rubber sole and heel in separate pieces. Figs. 4 and 5 are elevations of the foot-pressers I employ in carrying out my invention, and Figs. 6 and 7 are plans of Figs. 4 and 5.

Similar letters in all the figures represent similar or corresponding parts.

In carrying out my invention, instead of cutting the soles from sheets of india-rubber, as hitherto, I form the soles *a* separately, (in molds or otherwise,) of the required shape, and with a flange or plain border, *b*, all around, and with projections or ribs, and of the required width and strength, for the purpose of allowing the rubber sole *a* to be stitched onto the leather sole *c*.

To the ordinary boot-stitching machine, in place of the usual foot-presser, I adapt a foot-presser constructed either with one prong, *d*, as shown in Figs. 4 and 6, or with two prongs, *d' d'*, as shown in Figs. 5 and 7, for pressing on the flange *b* of the rubber sole *a*, during the stitching operation the needle passing at the side of the prong *d*, or through the space *e* between the prongs *d' d'*, whereby the stitching operation may be performed without injury to the rubber. I have found that the presser with one prong, *d*, is best suited for use when the flange *b* of the sole is required to be left narrow, and the presser with two prongs, *d' d'*, when the flange *b* is required to be left wider. I do not, however, in this application make any claim for a presser-foot of a sewing-machine, but illustrate the same, the better to show how my improved shoe or boot is outer-soled in a sewing-machine.

The india-rubber sole *a*, constructed as hereinbefore described and shown, is placed on the leather sole *c* of the shoe, a small portion of solution being advantageously employed to hold the same in place while being stitched. In stitching on the rubber sole the hereinbefore-described foot-presser presses the flange or border *b* closely against the leather sole *c*, while the needle passes through the leather sole *c* and the flange *b* of the rubber sole *a* and firmly stitches them together.

Lawn-tennis shoes having india-rubber soles

manufactured as hereinbefore described, may thus be "fair-stitched," which has not hitherto been practicable, and the rubber sole *a* will be as securely fixed to the leather sole *c* as an ordinary leather outer sole would be, and the india-rubber sole being stitched to the leather, and as this leather is blocked to the shape of the model or last on which it is made, the india-rubber sole is drawn up to the shape of the same, so as to produce an arch at the waist of the sole, and thereby improve the appearance and fit of the shoe, whereas when the india-rubber soles are cemented on as hitherto the same are flat and uncomfortable to the wearer.

Instead of the india-rubber soles and heels being formed in one piece, as hereinbefore described, and shown in Figs. 1 and 2, they may be made in separate pieces, as shown in Fig. 3, the hereinbefore-described flange *b* passing all round the sole and heel.

Instead of the india-rubber sole *a* being fair-stitched to the leather sole *c*, as hereinbefore described, the india-rubber sole may be sewed to the leather sole by the ordinary boot-sewing machine of the kind known as the "Blake and Goodyear boot-sewing machine," in which case the foot-pressers hereinbefore described, and shown in Figs. 4, 5, 6, and 7 would not be required.

The flange *b* of the india-rubber sole *a* may be formed with a groove to receive the stitches, and in all cases the stitches may, if required, be covered with a suitable cement.

In the drawings I have shown the india-rubber sole and heel formed with transverse projections or ribs of a triangular shape in section; but it will be evident that the projections of the sole may be of any other suitable shape—such as lozenge or pyramidal—or of an ornamental design, as may be required.

I am aware that a rubber outer sole has been split at its edges, then secured to another sole through a portion of such split edge, and the split parts then cemented together. My construction, however, differs materially from this, as it requires no splitting and no turning over or holding down during the sewing of any split portion, the sole being all solid, and having a complete rabbet or flange, which not only serves as a fixed guide while sewing, but also permits the thicker part between the flanges to protect the stitches from wear.

Having thus described my invention and the best means I am acquainted with for carrying the same into effect, I wish it to be understood that what I claim is—

In a lawn-tennis or other boot or shoe, an inner sole of leather, in combination with an outer sole, *a*, of rubber, made with a border or flange of lesser thickness than the main body of such outer sole, and united by a line of stitching through such flange to the leather sole, all as shown and described.

HENRY EDWARD RANDALL.
